UNITED STATES PATENT OFFICE.

WILLIAM J. DONNELLY, OF BUTTE, MONTANA.

DESIGN FOR A CROSS-HEART PENDANT.

51,201.

Specification for Design.

Patented Aug. 28, 1917.

Application filed July 7, 1917. Serial No. 179,279. Term of patent 14 years.

To all whom it may concern:

Be it known that I, WILLIAM J. DONNELLY, a citizen of the United States of America, residing at Butte, in the county of Silverbow and State of Montana, have invented a certain new, original, and ornamental Design for a Cross-Heart Pendant, of which the following is a specification, reference being had therein to the accompanying drawing, wherein—

The figure is a perspective view of a cross heart pendant, showing my new design.

I claim:

The ornamental design for a cross heart pendant, as shown.

In testimony whereof I hereunto affix my signature.

WILLIAM J. DONNELLY.
